UNITED STATES PATENT OFFICE.

HOWARD HENRY, OF KIRKSVILLE, MISSOURI.

MEASURING INSTRUMENT.

1,142,958.

Specification of Letters Patent. Patented June 15, 1915.

Application filed August 6, 1913. Serial No. 783,372.

To all whom it may concern:

Be it known that I, HOWARD HENRY, a citizen of the United States, residing at Kirksville, in the county of Adair and State 5 of Missouri, have invented certain new and useful Improvements in Measuring Instruments, of which the following is a specification, reference being had to the accompanying drawings.

This invention relates to new and useful 10 improvements in measuring instruments and more particularly to a combined miter and try square, the object of the invention being to provide a tool of this character for 15 making right and left miters and which at the same time will square the work without removing the tool therefrom.

Another object of the invention is the 20 provision of a measuring instrument of the above character which will possess advantages in points of efficiency and durability, is inexpensive of manufacture and at the same time is simple in construction and operation.

With the above and other objects in view, this invention consists in the novel features of construction and the combination and arrangement of parts to be hereinafter 25 more fully described, pointed out in the 30 claim and shown in the accompanying drawings, in which—

Figure 1 is a top plan view of a measuring instrument constructed in accordance with my invention. Fig. 2 is a side elevation illustrating the device applied. Fig. 3 is an end elevation, parts being broken away.

Referring more particularly to the drawings, 1 and 2 indicate two parallel side 40 members which are integrally connected at one end by means of the transverse member 3, the edges of which are tapering, as shown at 4, and terminate in an outwardly 45 extending end member 5 which is adapted to engage over the edge of a board or other work to which the device is to be applied so as to prevent lateral movement of the tool when in operation. Formed at the outer end of the member 5 is an outstanding 50 flange 6 which rests upon a platform or other surface upon which the board or work may be rested to steady the outer end of the tool and retain the same against lateral rocking movement when the device is applied to work, the thickness of which is less 55 than the transverse member 3. It will be

noted that when the member or flange 6 is placed upon a level surface, it will prevent any rocking movement of the side members 1 and 2.

It will be noted from the accompanying drawings that the outer longitudinal side edges of the members 1 and 2 are provided with the graduations 7 and are provided upon their inner longitudinal edges with 60 the V-shaped recesses 8 which are arranged in alinement with the larger of the graduations 7 whereby a pencil point may be arranged within these recesses to correctly 65 mark the work to which the instrument is applied. Thus, as illustrated in Fig. 1, the two positions of the pencil point 7^a show that any desirable angle may be readily obtained by the use of my improved instrument, the line of the angle being drawn 70 along the intersection of the two pencil points.

The spaced ends of the side members 1 and 2 are connected by means of a bar 9, the ends of which are secured, as shown at 80 10, to the ends of the side members to prevent the outer ends of said members from spreading should they be placed under strain. From this it will be seen that in applying my improved instrument to a 85 board or other similar piece of work, the vertically disposed end 5 is arranged over the edge of the board so that the graduations 7 will begin at the edge thereof whereby the person desiring to obtain the width 90 of the board may readily do so. Should it be desired to cut the work at an angle, the instrument will be laid upon the work as before and a pencil or other marking device will be arranged in any manner within the 95 recesses 8 according to the angle to be cut. The device is shifted to a diagonal angle across the work so that one of the longitudinal edges of one of the side members intersects the two pencil points so that a line 100 may be readily drawn between the two marks, indicating the angle upon which the work is to be cut.

It will be understood that the device may be used for marking blank boards longitudinally, when it is desired to rip the same by engaging the transverse member 3 with one side edge of the object and inserting a pencil point in any one of the notches 8. The side members are then moved along the 105 board, the pencil points passing over the upper face of the board and leaving a mark,

a predetermined width from either side of the board, whereby the object may be ripped along this line.

From the above description taken in connection with the accompanying drawings, it will be readily apparent that I have provided a simple and durable measuring instrument whereby right and left miters may be quickly and readily obtained by the tapering edges 4. It will also be apparent that the device, which is preferably constructed of sheet metal, is extremely simple in construction and can be manufactured at a comparatively low cost.

While I have shown and described the preferred form of my invention, it will be obvious that various changes in the details of construction and in the proportions may be resorted to for successfully carrying my invention into practice without sacrificing

any of the novel features or departing from the scope of the appended claim.

What I claim is:—

A device of the class described including a pair of parallel side members having their outer edges provided with graduations, a transverse outstanding piece integrally connecting the side members at one end, said transverse member extending the entire width of the side members, an outstanding flange formed integral with the transverse member, and a bar having its ends secured to the opposite ends of the side members. 25 30

In testimony whereof I hereunto affix my signature in the presence of two witnesses. 35

HOWARD HENRY.
